UNITED STATES PATENT OFFICE.

ARTHUR CLARKE SARGEANT, OF AGAWAM, MASSACHUSETTS.

DOORSTOP.

1,410,349.

Specification of Letters Patent. Patented Mar. 21, 1922.

Application filed December 15, 1920. Serial No. 430,826.

To all whom it may concern:

Be it known that I, ARTHUR CLARKE SARGEANT, a citizen of the United States of America, and a resident of Agawam, in the county of Hampden and State of Massachusetts, have invented a new and useful Doorstop, of which the following is a specification:

My invention relates to improvements in devices for holding doors in open position,

10 and is designed especially for use in connection with large and heavy, outwardly-swinging doors, such as those used in garages, and consists essentially of a swivel member supported usually from the top of a door frame or casing, which member is perforated and equipped with an oscillatory latch and a spring-pressed pin or plunger, and a latch- and plunger-engaging member pivotally connected with the door, and operating in or 15 through said first-named member in operative relation to said latch and plunger, the latter being adapted to cooperate with said latch- and plunger-engaging member to assist in retaining the same in engagement 20 with said latch, together with such other parts and members as may be necessary or desirable in order to render the device complete and serviceable in every particular, all 25 as hereinafter set forth.

30 The present device is in the nature of an improvement of the door stop covered by United States Letters Patent, No. 1,352,147, issued to me September 7, 1920, and the latch, of which mention has been made, is 35 similar to that which forms a part of the previous invention.

The primary object of my invention is to 40 provide a stop, of the class described, which is applicable for use in connection with a heavy swinging door, at the top of such door where said stop is out of the way, and which is capable of securely holding the door in open position, such stop being readily attached to almost any door casing and door, 45 automatic in the engaging operation when the door is opened, and semi-automatic in the releasing operation when the door is closed, strong, and durable, convenient, and with entirely practicable and highly efficient.

50 This stop can be used in connection with a door that has no spring, or, in other words, with a door that is not self-closing, and will more frequently be employed with such a door than with one which is self-closing.

55 Another object is to provide a stop which

holds a door so safely and securely that the latter is not liable to be accidentally closed by the wind or other agency, but only with the hands and at such times as it may be desired to close said door.

I attain the objects and secure the advantages of my invention by the means illustrated in the accompanying drawings, in which—

Figure 1 is an elevation of a door stop which embodies a practical form of my invention (the same being applied to a door casing and door), as viewed from the inside when the door is closed; Fig. 2, a side elevation of the parts and members disposed as in the first view, a portion of the latch rod or bar being broken out to economize space; Fig. 3, a side elevation of the parts and members of the stop disposed as when the door is open, only the free terminal portion of said latch bar appearing, however, and the door being omitted, in order to economize space; Fig. 4, a bottom plan of the stop showing the members disposed as when the door is open, parts being broken out of the door casing, door, and latch bar, to save space as before; Fig. 5, an inside elevation of the latch support and latch, and a cross section through the latch bar and showing the lug thereon in locking engagement with said latch, these parts being disposed as in the two preceding views; Fig. 6, a bottom plan of the latch; Fig. 7, a top plan of the free terminal portion of the latch bar showing the lug thereon, and, Fig. 8, a broad side elevation of the perforated portion of said latch support.

Similar reference characters designate similar parts throughout the several views.

In the general views fragmentary portions of a door jamb, a door lintel, and a door are represented at 1, 2, and 3, respectively. In Figs. 1, 2, and 3 the lintel 2 is shown in section, and in Figs. 2 and 4 the door 3 also is shown in section. The jamb 1 appears in Fig. 2 wherein the same is in elevation, and in Fig. 4 wherein it is in section. The door is in elevation in Fig. 1, and in section in Figs. 2 and 4. One of the hinges, by means of which the door 3 is connected with and supported from the jamb 1, is represented at 4 in Fig. 4.

One element of this door stop is a freely-suspended, swinging latch 5. This latch corresponds with one of similar construction which forms a part of the subject mat-

ter of the hereinbefore-mentioned patent, and the same will be briefly described before entering into a detailed description of the new elements of the present stop.

5 The latch 5 has an arcuate bottom edge concentric with a bolt 29 which is the direct support and center upon which said latch swings. On this arcuate bottom 6 is a keeper 7. The bolt 29 passes rearwardly or 10 inwardly through the latch 5 and a vertical support or hanger 8, and one side of said latch is contiguous with such hanger. The keeper 7 extends obliquely across the bottom 6, from the side of the latch 5 which is contiguous to the hanger 8 to the opposite side 15 of said latch, and a notch 9 is formed in the outer or forward end of said keeper. The bottom of the keeper 7 is concentric with the bottom of the latch 5. The notched end of 20 the keeper 7 may be termed the operating end of said keeper, to distinguish it from the end of the keeper which is contiguous to the hanger 8. The keeper 7, with the notch 9 therein, is so constructed and arranged on the latch bottom 6 that said keeper has a short side 10 and a long side 11, the former being the nearer to the hanger 8.

Passing now to the new elements, it will be seen that a plate 12, is securely attached 30 to the under side of lintel 2, and the hanger 8 has a horizontal part 30 which is pivotally connected to said plate in such a manner as to enable said part and the hanger as a whole to swivel or turn upon and about 35 the axis thus provided. In the present instance a lag-screw 13 is employed as the pivotal support for the hanger 8, the part 30 being held in rubbing contact with the plate 12, and permitted to be rotated on the 40 axis provided by said screw or pivot. The lag-screw 13 passes upwardly through the part 30 into the plate 12. The latch 5 is pivotally connected with the hanger 8, beneath the horizontal part 30 thereof, by 45 means of the bolt 29, as previously observed. The bolt 29 is held in place with the aid of a nut 14 which is on the inner, protruding terminal of said bolt, that is to say, the terminal of the bolt which extends beyond the 50 inner or rear face of said hanger. The nut 14 must not, of course, be tight enough to prevent the latch 5 from oscillating freely and by gravity on the bolt 29. The plate 12 may in some cases be omitted. There is an 55 inverted T-shaped slot 15 and a round hole 16 in the hanger 8. The slot 15 and the latch 5 are in such position relatively that the latter overhangs the upstanding branch of said slot, or, in other words, the lower 60 portion of the keeper 7 of said latch is normally in front of the aforesaid branch of said slot. The hole 16 is below the slot 15.

A spiral-spring 17 and a headed pin or plunger 18, the shank of the latter being in 65 said spring, are received in the hole 6. The

spring 17 has its inner terminal, as 19, expanded or otherwise arranged to engage the inner or rear face of the hanger 8, so as to prevent said spring from being thrust forwardly out of said hanger and so becoming 70 detached therefrom. The plunger 18 has at the outer end a head 20 to which the corresponding end of the spring 17 is attached. The parts are so proportioned that normally the plunger 18 is disposed with a portion thereof forward of and a portion thereof behind the hanger 8, as best shown in Fig. 2.

A horizontal latch rod or bar 21 is slidably arranged in the horizontal, bottom part of the slot 15 in the hanger 8, and said bar has on top and adjacent to the inner or rear end thereof a lug 22 which is capable of passing through the vertical, upper part of said slot. The outer or front terminal of the bar 21 is pivotally connected at 23 with an angular bracket 24 secured to the inside of the door 3. At the inner end of the bar 21 is a depending lug 25. The latch 7 is normally in the path of the lug 22, and the rear 90 end of the plunger 18, which end protrudes behind the hanger 8, is in the path of the lug 25. The lug 22 is preferably of the shape shown in the drawings and more especially in Fig. 7, in order to facilitate engagement of said lug with the latch keeper 7. As here presented the lug 22 is arranged obliquely on the latch bar 21, and the narrower, vertical edges of said lug are angular to provide beveled surfaces for the more 100 convenient contact with the keeper 7.

When the door 3 is closed, the latch bar 21 is approximately at right-angles to said door and extends some little distance beyond the back side of the hanger 8, the latter is approximately at right-angles to the jamb 1, and the latch 5 hangs vertically—see Figs. 1 and 2. But when the door 3 is opened, the bar 21 is drawn outwardly with said door, the hanger 8 swiveling or turning 110 on the pivot 13 to enable this to be done. The same relative angular position of the bar and hanger with attached latch is maintained, and is always the same, but the bar now forms an obtuse angle with the door, and the hanger is no longer at right-angles to the jamb 1. The bar 21 is long enough to enable the door 3 to be opened to its full extent, usually at an angle of 45 degrees. As the door approaches its wide-open position the lug 22 passes through the slot 15 and encounters the short side 10 of the keeper 7, with the result that the latch 5 is rocked on its pivot 29, toward the jamb 1, in such a manner as to enable said lug to enter the notch 9. The part of the lug 22 that first contacts with the keeper 7 is indicated at 120 26 in Fig. 5, and the part of said lug which enters the notch 9 is represented at 27 in Figs. 1 and 7. Naturally the lug 22 is not of suffi- 130

cient height to encounter the latch 5 above the keeper 7. Just before the lug 22 engages the notched end of the keeper 7, the lug 25 contacts with the rear end of the plunger 18 and forces said plunger forwardly against the resiliency of the spring 17. The parts are now disposed as shown in Figs. 3, 4, and 5. The spring 17 tends to force the plunger 18 rearwardly, owing to which fact and the further fact that said plunger is bearing on the lug 25, the bar 21 with the door 1 is urged rearwardly or inwardly, and consequently the lug 22 is held in engagement with the notched end of the keeper 7. The door 3 cannot be closed because the latch 5 with its keeper is interposed between the lug 22 and the hanger 8. Any movement of the door 3 in the direction to open the same wider is overcome by the spring 17, acting through the plunger 18 and the lug 25 on the bar 21.

To unlock or release the door 3, push it open a little farther, exerting sufficient force to overcome the resistance of the spring 17, so as to cause the lug 22 to pass out of the notch 9 and beyond the keeper 7. Then the door is pushed into closed position, the lug 22, which was first actuated forward, now moving backward with the bar 21. As the lug 22 moves rearwardly, it bears first with the edge surface 32, Fig. 7, on the side 11 of the keeper 7, as the latch 5 swings down from the position it occupies in Fig. 5 and certain of the other views, and forces said latch into a tilted position in the opposite direction, said latch swinging on the pivot 29 in all cases. As soon as the lug 22 passes rearwardly beyond the keeper 7, the latch 5 swings back into its normal, vertical position, as represented in Figs. 1 and 2. The lug 22 has passed through the slot 15 in the hanger 8 and some distance beyond said hanger by the time the door is completely closed. Meanwhile the lug 25 passes away from the plunger 18 and is finally located at a considerable distance from the same. During the inward travel of the bar 21 the hanger 8 swings on the pivot 13 until said hanger assumes the normal or former position and is finally in approximately parallel relationship with the closed door. The bar 21 causes the hanger 8 to swivel as said bar is moved forward and backward through said hanger, otherwise, that is, if the hanger were stationary, the parts would bind and be inoperative. The spring 17 acts to thrust the plunger 18 rearwardly as soon as the latter is released by the lug 25. The stop is now ready for a repetition of the locking operation when the door is again opened.

The hanger 8 supports both the latch 5 and in part the latch bar 21. When the door is closed by far the greater portion of the bar 21 projects rearwardly from the hanger 8, and said bar is supported at all times by said

hanger and the bracket 24. The bolt 23 passes downwardly through the horizontal part of the bracket 24 and through the bar 21 to receive a nut 28 on the lower, protruding terminal thereof. The nut 28 directly supports the outer terminal of the bar 21 from the bracket 24, and must be loose enough to permit said bar to oscillate on the bolt 23.

The bar 21, as herein presented, consists of a member that is flat in cross section and therefore better adapted for my purpose than would be a bar or rod of some other shape in cross section.

The bottom of the keeper 7 is arcuate like the bottom of the latch 5 and concentric therewith, so that said latch can swing with said keeper quite closely to the bar 21 without contacting therewith.

Although this stop is designed more especially for use with a door that has no spring and is not, therefore, self-closing, it can be employed with a door of the self-closing type, as hereinbefore observed or intimated.

More or less change in the shape, size, construction, and arrangement of some or all of the parts of the door stop may be made without departing from the spirit of my invention or exceeding the scope of what is claimed.

What I claim as my invention, and desire to secure by Letters Patent, is—

1. The combination, in a door stop, with a support attachable to a door frame, and a freely-swinging gravity latch carried by said support, said latch having a keeper on the bottom, of a member adapted to be pivotally connected with a door and to move longitudinally beneath said latch and having a part to engage said keeper, said member and latch normally being out of contact.

2. The combination, in a door stop, with a support attachable to a door frame, a freely-swinging gravity latch carried by said support, and a spring-pressed member also carried by said support, of a member adapted to be pivotally connected with a door, and having a part to engage said latch and a part to engage said spring-pressed member.

3. The combination, in a door stop, with a swivel support attachable to a door frame, and a freely-swinging gravity latch carried by said support, of a member adapted to be pivotally connected with the door, and having a part to engage said latch.

4. The combination, in a door stop, with a swivel support attachable to a door frame, a freely-swinging gravity latch carried by said support, and a spring-pressed member also carried by said support, of a member adapted to be pivotally connected with a door, and having a part to engage said latch and a part to engage said spring-pressed member.

5. The combination, in a door stop, with a
perforated support attachable to a door
frame, and a freely-swinging gravity latch
carried by said support and overhanging the
perforation therein, said latch having a
keeper on the bottom, of a member adapted
to be pivotally connected with a door and
operating in said perforation beneath said
latch, said member having a part to engage
10 said keeper, and normally being out of con-
tact with said latch.

6. The combination, in a door stop, with a
perforated support attachable to a door
frame, a freely-swinging latch carried by
15 said support and overhanging one of the
perforations therein, and a spring-pressed
member also carried by said support and
operating in the other perforation therein,
of a member adapted to be pivotally con-
20 nected with a door and operating in said
first-named perforation, said last-named
member having a part to engage said latch
and a part to engage said spring-pressed
member.

25 7. The combination, in a door stop, with
a perforation swivel support attachable to a
door frame, and a freely-swinging gravity latch
carried by said support and overhanging
the perforation therein, of a member
30 adapted to be pivotally connected with a
door and operating through said perfora-
tion, said member having a part to engage
said latch.

35 8. The combination, in a door stop, with a
perforation swivel support attachable to a
door frame, a freely-swinging gravity latch
carried by said support and overhanging one
of the perforations therein, and a spring-
40 pressed member also carried by said support
and operating in the other perforation therein,
of a member adapted to be pivotally con-
nected with a door and operating in said
first-named perforation, said last-named
45 member having a part to engage said latch
and a part to engage said spring-pressed
member.

9. The combination, in a door stop, with a
vertical hanger pivotally supported from a
door lintel, and having an opening therein,
50 and a latch pivotally connected with said
hanger and overhanging said opening, of a

bar operating in said opening and adapted
to be pivotally connected with a door, said
bar having a lug thereon to be engaged by
and released from said latch when said door
55 is opened and closed, and said opening being
large enough to admit of the passage of
said lug.

10. The combination, in a door stop, with
a hanger pivotally supported from a door
lintel, said hanger having openings therein,
and a latch pivotally connected with said
hanger and overhanging one of said open-
60 ings, and a spring-pressed plunger in the
other of said openings, of a bar slid-
ingly arranged in said first-named opening
and adapted to be pivotally connected with a
door, said bar having a lug which is capable
65 of passing through said first-named opening
to be engaged by and released from said
latch when said door is opened and closed,
and said bar having a lug at the free end to
engage said plunger and compress said
70 spring when said door is in open position,
whereby said first-named lug is held in en-
gagement with said latch.

11. The combination, in a door stop, with
a vertical hanger having a horizontal part
which is adapted to be pivotally connected
with a door lintel, said hanger having open-
80 ings therein, a latch pivotally connected
with said hanger and overhanging one of
said openings, and a spring-pressed plunger
in the other of said openings, of a bar slid-
ingly arranged in said first-named opening
85 and adapted to be pivotally connected with
a door, said bar having a lug which is capa-
ble of passing through said first-named open-
ing and into and out of engagement with
said latch when said door is opened and
90 closed, and said bar having at its free end
a lug adapted to engage said plunger and
actuated the same against the resiliency of
its spring when said door is in open posi-
tion, whereby said first-named lug is re-
95 tained in locking engagement with said
latch.
